H. S. ROSS.

WRENCH.

No. 75,199.

Patented Mar. 3, 1868.

United States Patent Office.

H. SCHUYLER ROSS, OF BUFFALO, NEW YORK, ASSIGNOR TO CHARLES G. ROSS, OF NEW YORK CITY.

Letters Patent No. 75,199, dated March 3, 1868.

IMPROVEMENT IN WRENCHES.

The Schedule referred to in these Letters Patent and making part of the same.

TO ALL WHOM IT MAY CONCERN:

Be it known that I, H. SCHUYLER Ross, of the city of Buffalo, in the county of Erie, and State of New York, have invented a new and improved Wrench; and I do hereby declare that the following is a full, clear, and exact description of the same, reference being had to the annexed drawing, forming part of this specification, in which—

Figure 1 is a perspective view of my invention.

Figure 2 is a vertical longitudinal section thereof, taken on the plane of the line z z , fig. 1.

Figure 3 is a side elevation thereof, showing the jaws opened.

Figure 4 is a modification, showing a spring for opening the sliding jaw.

Figure 5 is another modification, showing another manner of constructing and arranging the sliding jaw.

My invention consists in the combination, for the purpose of providing a nut or pipe-wrench of an improved construction, of a cam, an outer jaw, and an inner jaw, the latter arranged to travel along the bar of the wrench, and operated by the cam in such manner as to cause the inner or sliding jaw to advance toward the outer jaw, to clamp the article placed between the jaws, and the several parts being so constructed and arranged that the greater the force exerted on the handle to turn the wrench, the firmer becomes the bite of the jaws.

A designates the outer jaw, B the sliding or inner jaw, fitted to travel along the bar C, D the cam for operating the inner jaw, and E the handle. These are the principal parts of the wrench, and can all be made of malleable iron. The jaw A and bar C are shown as being cast in one piece. The bar C is slotted (see fig. 1) for its entire length, the two sides embracing the handle E, or the rear part of the cam D, where they are pivoted thereto. Through this slot in the bar passes the lower end or shank of the sliding jaw B, it being held in place by a head, a , as seen in fig. 1. Instead of making a slot entirely through the bar C, as shown in fig. 1, I can make grooves in said bar C, and give a corresponding shape to the shank of the jaw B, (see fig. 5,) and the said jaw would travel along the bar C, as desired. In order to provide a means for increasing the angle of the handle, should it be necessary, in order to get access to some nut or pipe to be turned, I provide a second aperture or hole, b , in the handle, where the bar C can be pivoted. A groove, c' , corresponding in curve to the curved end of the cam D, is made in said cam, and a pin or hook, h , on the jaw B, is fitted to travel therein. This is a simple means I adopt for drawing back the jaw B, it being obvious that this drawing back of the jaw B can be effected by simply turning the handle in a direction opposite to that in which it would be turned to unscrew the nut, as will become apparent by reference to figs. 1 and 3, the jaws being shown closed in the former figure, and open in the latter. As an equivalent for this pin and groove, I have shown in fig. 4 a spiral spring, located between the jaws A and B, which would effect the same purpose.

It will be seen from the above description that the end of the cam always bears against the sliding jaw, and that the more operation of the handle in the necessary direction to turn the nut closes the jaws, and that the harder the handle is pushed to turn the nut the firmer becomes the bite of the jaws. Great strength in a wrench is obtained by such construction.

A modification of my wrench can be constructed by making the cam D a perfect eccentric, turning on the pivot, and made of such diameter as to allow the same to pass under and back of the jaw B, when closed, so that on continuing its motion backward through the slotted bar C, it will again cause the sliding jaw B to recede down the slotted bar C, and on reversing its motion the sliding jaw will be advanced toward the outer jaw and clamp the article placed between them, as in the former case, thus producing a wrench that will turn a nut or other object in either direction, without turning the wrench over or changing its position.

A further modification may be made by making the slot of the bar C at right angles with its shown position, and so placing the pivot that the handle E and cam D will move or vibrate sidewise, or at right angles with the movement shown in fig. 3, thus allowing the ends of the jaws to be used to clamp an article placed between them.

I am aware that a patent has been granted to Alfred Sower and Martin Payne, May 12, 1863, for a machine for punching railroad-rails, in which a punch is operated by a cam and slot or groove; this I do not claim, but

What I do claim, and desire to secure by Letters Patent, is—

1. A wrench composed of a stationary jaw, A, a movable jaw, B, cam D, and handle E, constructed and arranged substantially as and for the purpose specified.

2. A wrench having its movable jaw B operated by a cam D, pin h , and groove C, or their equivalents, substantially as herein specified.

H. SCHUYLER ROSS.
